UNITED STATES PATENT OFFICE

GEORGE ERNST, OF NEWARK, NEW JERSEY

GAUGE GLASS CONNECTER

Application filed April 20, 1927. Serial No. 185,142.

This invention relates to steam boiler attachments and has particular reference to gauge glasses adapted for use on large or high pressure steam boilers.

5 In the usual practice of gauge glasses for large boiler constructions, the glass proper is connected to and detached from the valve body mechanisms by means of large metallic glands or couplings, which being made of metal and of massive formation for strength, are very dangerous when manipulated in connection with the gauge glasses which are apt to be broken or at least scratched or chipped by the metallic fittings with the result that 10 when the steam pressure is brought to bear upon the glasses they are almost certain to explode due to the chipping or scratching.

Among the objects of this invention, therefore, is to provide gauge glass connections or 15 connectors in which there is no packing gland nor connector of screw threaded type embracing or surrounding the glass, and consequently the above mentioned likelihood of damage or breakage to the glass cannot occur.

20 Another object of the invention is to facilitate the operation of repacking or replacing the sight glass of a gauge glass mechanism.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a side elevation of a preferred embodiment of the invention applied to a vertical glass, but it is to be understood that the glass might be arranged otherwise than vertical if desired.

Fig. 2 is a plan view of the same.

45 Fig. 3 is a front elevation of the upper portion of Fig. 1, looking toward the left.

Fig. 4 is a vertical section on the line 4—4 of Fig. 3.

50 Fig. 5 is a vertical section on the line 5—5 of Fig. 4.

Fig. 6 is a view similar to Fig. 5, but with the sealing mechanism open.

Fig. 7 is a transverse sectional detail on the line 7—7 of Fig. 3.

Referring now more specifically to the drawings, I show upper and lower valve bodies 10 and 11 which as usual are tapped into a steam boiler or water column in a well known manner, and each provided with a normally open cut-off valve 12 having a stem 13 to 55 which is connected a bar, wheel, or other mechanism 14 for operating the same from the floor or from a distance. A gland 15 surrounds the stem 13 and is screw threaded upon the main portion of the valve body as is well understood in this art. The valve 12 is preferably of the type which is flexibly connected to the stem at 16 and hence is self centered for closing upon the seat 17.

Extending laterally, up or down, from each valve body is a boss or socket piece 18 to receive the adjacent end of the glass 19 as heretofore but with the exception that the boss is preferably smooth and of hollow cylindrical form instead of being threaded up 70 on the outside to receive a packing or sealing member in the nature of a gland.

On another side of the valve body preferably diametrically opposite from the boss 18 is secured or arranged in any convenient manner a socket member 20 for the reception of the head 21 of a screw 22 in the nature of a jack screw, the screw passing outward more or less freely through a hole 23 formed centrally of the socket member.

85 In the old practice of gauge glasses in connection with the heavy nuts or couplings that were slipped upon the glass and thereby held temporarily, there were used commonly heavy metal collars which likewise had to be slipped upon the glass accompanied by the danger above described, the collars being intended to abut against rubber gaskets 24. Instead of using metal collars or the like that slip along the glasses 29 for abutment relation with the 90 gaskets 24, I use only a split collar for each gasket, said collar comprising two parts 25a and 25b being semi-cylindrical in nature and adapted to loosely embrace the glass 19 and to abut directly against the gasket 24 as shown 100

in Figs. 4 and 5. These collar members 25a and 25b are attached as by rivets or screws to a pair of hangers 26 extending parallel thereto and pivoted at 27 to a cross head 28 through which the screw 22 is threaded, the screw, cross head, and hangers constituting what may be termed a clamp. The end of the screw 22 remote from the head 21 is provided with a thimble 29 held in place thereon by means of a finger piece or bar 30. The collar member 25a is provided with a pair of ears 31 which have holes to receive a similar number of pins 32 carried by the other collar member 25b.

15. In inserting a glass in accordance with this invention, the valve bodies having been put in place and properly aligned, the glass 19 is slipped into place loosely into the bosses 18 of the oppositely arranged heads, the gaskets 24 having first been slipped upon the ends of the glass, and the clamps are then brought into position, from that of Fig. 6 to that of Fig. 5. When the collar members 25a and 25b are brought together on opposite sides of the glass, the pins 32 are caused to enter the holes in the ears 31, the looseness at the cross head and head 21 of the screw providing for this adjustment at the collar members. So the smaller ends of the collar members come into place against the outer end of the gasket 24. The outer surfaces of the collar members have closer contact with the inner surface of the boss 18 than with the glass. Consequently there is no immediate likelihood that the bringing of the collar members into sealing position will disturb or damage the glass itself. After the collar members are brought into position as just described, the jackscrew 22 is rotated in a right hand direction with the immediate effect of drawing the cross head 28 away from the valve body or as from the position of Fig. 6 to that of Fig. 5. This action of the screw puts the clamp under strain and forces the collar members toward the axis of the valve, compressing the gasket and making it impossible for the clamp to become accidentally loosened. And nothing touches the glass at any time except the rubber gaskets. On the reverse operation, to release the clamp, the screw 22 is turned in a left hand direction, and since the head 21 of the screw is locked from endwise movement toward or from the axis of the valve, the continued left hand rotation of the screw causes 45 positively the collar members 25a and 25b to recede from not only the gasket, but free from the boss 18. This mechanism is easily manipulated, the amount of force required for compressing the gasket being relatively small compared with the power inherent in the jack screw 22 and cross head. The mechanism in no manner obstructs the vision of the glass inasmuch as the collar members 25a and 25b occupy no more space lengthwise of the glass 55 than the ordinary coupling or gland nut.

Moreover, the readjustment, retightening, or resetting of the gauge glass may be performed easily and quickly by this new arrangement.

I claim:

1. In a gauge glass connector, the combination with a body and a gauge glass to be connected therewith, of a clamp carried by the body adjacent to the same, a gasket surrounding the gauge glass within the body, means for compressing the gasket, and manually operated means exterior to the body for actuating the first mentioned means for putting the gasket under compression, said first mentioned means including a split collar surrounding the gauge glass and bearing on the gasket. 70

2. The combination with a body adapted to receive an end of the gauge glass to be connected therewith, and a compressible gasket surrounding the gauge glass, of a structure 85 carried by the body and having means to compress the gasket, a pair of hangers carrying said means, a cross head to which the hangers are connected, and manually operated means for putting the cross head under tension to cause said means to compress the gasket, said means and said manually operated member being positioned on opposite sides of the body. 90

3. In a gauge glass connector, the combination with a valve body, a gauge glass, and a gasket, of a split collar to compress the gasket, and means comprising a clamp carried by the outside of the valve body and accessible independently of the valve mechanism, said clamp comprising a pair of members individually engaging the parts of the split collar. 100

4. In a gauge glass connector, the combination with a valve body, a gauge glass, and a gasket surrounding the glass for co-operation with the valve body, of compression means for the gasket comprising a pair of mating collar members spanning loosely the glass and abutting against the gasket, a pair of hangers carrying the collar members, a cross head to which the hangers are connected, and manually operated means for putting the cross head under tension to cause the collar members to assume their sealing position. 110

5. The combination with a body and a gauge glass slipped thereto, of sealing means for the gauge glass comprising a split collar spanning the gauge glass, hanger members separately carrying the collar portions, and manually operated screw means acting to draw the hanger members and both collar portions simultaneously so as to compress the sealing means. 115

6. The combination with a head, and a gauge glass, of a gasket in said head to seal the glass therein, a split collar surrounding the glass, spaced elements to act individually on the portions of the split collar to compress the gasket, and means on the head to actuate said spaced elements. 125

7. The combination with a head and a

gauge glass, of a gasket in said head to seal the glass therein, and means including a split gland to compress the gasket, and other means pivotally mounted at a point lying in

5 the longitudinal axis of the glass to exert individual relatively balanced pressures on the portions of the gland.

8. The combination with a head, and a gauge glass, of a gasket in said head to seal

10 the glass therein, a split collar providing portions having interlocking means, spaced elements to individually act on the portions of the collar to compress the gasket, and means on said head including a cross head to actuate said spaced elements.

9. A device including a gauge glass, a head therefor, a gasket in the head, a split gland for the gasket, swingable means for releasably bearing on the gland without torsional

20 strain on the glass, and means for mounting and exerting a force on the swingable means in a direction axial with the gland for causing the latter to compress the gasket.

10. The combination with a head, and a gauge glass, of a gasket in the head to seal the glass therein, a split gland surrounding the glass, and spaced elements external of the head and mounted to act as a unit on the respective split gland portions to compress

30 the gasket.

11. A device of the character described, including a gauge glass, a head therefor, a gasket in the head, a gland for the gasket, and swingable means mounted on the head

35 and adapted to act on the gland to compress the gasket.

In testimony whereof I affix my signature.
GEORGE ERNST.
